UNITED STATES PATENT OFFICE

JAMES F. HINES, OF LAKESIDE, OHIO

MOLDING FLASK

Application filed January 2, 1926. Serial No. 78,795.

My invention relates to molding flasks and the principal object of my invention is to provide a new molding flask improved particularly in the construction of the sand retaining means.

In the drawings accompanying this specification and forming a part of this application I have shown, for purposes of illustration, one form which my invention may assume.

10 In these drawings:

Figure 1 is a side elevation of a flask embodying this illustrative embodiment of my invention.

15 Figure 2 is a plan view of the flask shown in Figure 1, while

Figure 3 is a detail view illustrating the sand strips in greater detail.

This application is a continuation in part 20 of my copending application Serial Number 720,218.

The flask shown herein comprises a cope section 30 and a drag section 31, the cope section 30 comprising side members 32 and end members 33 each provided at each end with a recess 34 arranged to cooperate with the corresponding recess of the adjacent member to form an aperture into which may be cast a retaining lug 35 effective to hold the two members firmly and rigidly assembled, the drag section 31 being similarly formed, and the construction being set forth in more detail in my application for mold containers filed concurrently herewith.

Pivoted to the lower face 36 of each side member 32 of the cope 30, by means of two pivot screws 37 positioned adjacent the center of the side member 32 and secured to the side member 32, are a pair of sand strips 38 receiving the pivot screws 37 through apertures 39, and movable in recesses 40 in the lower face 36 of the side member 32 between the position illustrated at the left in figure 3 wherein the strips 38 are withdrawn flush with the inner surface of the flask and therefore inactive, and the position illustrated at the right in figure 3 wherein the sand strips 38 project beyond the inner surface of the flask and are therefore effective to support the sand within the cope section 30.

50 Throughout this movement the sand strips

38 are supported by the heads of the pivot screws 37 and also by the heads of screws 41 which depend from and are fixed to the side members 32 and extend through slots 42 in the sand strips 38 elongated to permit this movement but effective, in cooperation with the screws 41, to limit the movement of the sand strips 38 to between the two positions illustrated.

With this construction I find it convenient 60 to secure the pivot screws 37 to the side members 32 by screwing the pivot screws 37 into tapped holes 43 in the side members 32, and to secure the holding screws 41 in position on the side members 32 by inserting them in nuts 44 cast into the flask section securing lugs 35. Under these circumstances, however, it is extremely difficult to accurately position these nuts 44 and I therefore find it 65 advisable to provide for some variation in the position of these nuts 44 by elongating the pivot apertures 39 to permit longitudinal adjustment of the sand strips 38 commensurate with the variation in positioning of each holding screw nut 44.

70 It will be understood by those skilled in the art that in the event I desire additional support for the cope section of the mold I may duplicate upon the end members 33 of the cope section 30 the sand strip means 75 herein shown as applied only to the side members 32 of the cope section 30.

It will be apparent that the sand strips herein illustrated project into the mold the greatest extent at the corners where the casting is normally farthest removed from the exterior of the mold, and to the least degree at the centers of the sides where the casting is normally least removed from the exterior 80 of the mold, and it will therefore be obvious 85 that the strips herein illustrated support the cope section of the mold with the minimum weakening thereof.

90 From the above description it will be obvious to those skilled in the art that I have provided new and improved sand strip means. At the same time, it will also be obvious to those skilled in the art that the particular embodiment of my invention herein shown 95 and described may be variously changed and 100

modified without departing from the spirit of my invention or sacrificing the advantages thereof.

It will therefore be understood that the disclosure herein is illustrative only and that my invention is not limited thereto.

I claim:

1. A flask comprising a polygonal shell having sand strip means on certain sides thereof each comprising means arranged, when advanced into the mold space, to extend into said space to a greater extent adjacent the ends of the side than centrally of said side.
2. A flask comprising a polygonal shell having sand strip means on certain sides thereof each comprising two sand strips pivoted on vertical pivot means centrally of the side of the flask and extending therefrom in opposite directions along said side and thus arranged, when advanced into the mold space, to extend into said space to a greater extent adjacent the ends of the side than centrally of said side.
3. Sand strip means for a flask comprising a sand strip, pivot means connecting said sand strip to said flask to permit said sand strip to be swung in a horizontal plane about a vertical pivot into and out of operative position, arcuate guiding means effective to connect said sand strip to said flask remote from said pivot means while permitting such swinging of said sand strip, said pivot means being loose to accommodate for variations in said arcuate guiding means or in the spacing of said arcuate guiding means from said pivot means.
4. Sand strip means for a flask comprising a sand strip, pivot means connecting said sand strip to said flask to permit said sand strip to be swung in a horizontal plane about a vertical pivot into and out of operative position, arcuate guiding means effective to connect said sand strip to said flask remote from said pivot means while permitting such swinging of said sand strip, said pivot means being loose to accommodate for variations in said arcuate guiding means or in the spacing of said arcuate guiding means from said pivot means, said pivot means comprising a stud carried by said flask and extending through an aperture in said sand strip elongated longitudinally of said sand strip, and said arcuate guiding means comprising a stud carried by said flask and extending through an arcuate slot in said sand strip.

In testimony whereof I hereunto affix my signature.

JAMES F. HINES.
